UNITED STATES PATENT OFFICE.

WILLIAM H. STARR, OF DECATUR, ILLINOIS.

DESIGN FOR A GIRDLE.

SPECIFICATION forming part of Design No. 27,422, dated July 27, 1897.

Application filed March 1, 1897. Serial No. 625,671. Term of patent 3½ years.

To all whom it may concern:

Be it known that I, WILLIAM H. STARR, of Decatur, in the county of Macon and State of Illinois, have invented a certain new and useful Design for Girdles, of which the following is a specification.

The design is illustrated in the drawings forming part of this specification, in which—

Figure 1 is a face view of the girdle, and
10 Fig. 2 is an edge view of the same.

The characteristic feature of the design is a belt composed of a set of conjoined links 1, each perforated centrally and contracted at point of conjunction in such manner that the
15 edges of the body portion of the girdle are composed of numerous convexities, each forming with its neighbor an angular notch, and a ribbon, as 7, run sinuously through the perforations of the links.

At one end of the body of the girdle is a 20 buckle 4. At the other end is a strap 5, having a set of holes 6, and loops 3 are fastened to the body portion in the vicinity of the buckle; but these details have little to do with the design.

25 What I claim as new, and desire to secure by Letters Patent, is—

The design for a girdle as herein shown and described.

In testimony whereof I sign my name in the 30 presence of two subscribing witnesses.

WILLIAM H. STARR.

Attest:

EDWARD M. STARR,
WILBER C. BULLARD.
